UNITED STATES PATENT OFFICE

WILLIAM CLARENCE GARMAN, OF GALVESTON, TEXAS

AUTOMOBILE HOOD VALLEY

Application filed December 19, 1932. Serial No. 648,010.

This invention relates to eaves or gutters for automobile hoods to protect the ignition system of the automobile against saturation with moisture during prolonged rains or violent storms.

The primary object of the present invention is to provide for this purpose an eave, gutter or valley which may be sold as a separate article and may be applied to automobiles already constructed simply by placing the valley in position and without any need to in any way permanently secure the valley to any part of the automobile and also without any need to in any way modify the construction of either the valley or the automobile, whereby the valley may be placed in position by the purchaser without the need of the services of a mechanic and without any operation involving any possible risk of marring the finish of the automobile hood or adjacent parts.

In the accompanying drawing:

Figure 1 represents a conventional view of the top portion of the hood and adjacent parts of an automobile, the hood being sectioned along its central hinge and the engine and other parts being conventionally shown in side elevation;

Figure 2, a perspective view, broken away, of my invention;

Figure 3, a top plan view thereof;

Figure 4, a fragmentary sectional view on line 4-4 of Fig. 5, looking in the direction of the arrows; and

Figure 5, a fragmentary sectional view on line 5-5 of Fig. 4, looking in the direction of the arrows.

Referring now in detail to the drawing, A designates the cowl; B, the radiator; C, the hood; D, the oppositely presented horizontal hood supporting flanges extending toward each other from the adjacent faces of the cowl and radiator respectively; D', the usual central recesses, sockets, or bearings formed in the flanges D for receiving, supporting, and positioning the extreme end portions of the central hood hinge rod F; and E, the usual packing lacings through holes in the respective flanges D.

All parts referred to in the immediately

preceding paragraph are old and well known, being usual features universally in use in practically all automobiles, and form no part of the present invention but are thus very briefly referred to simply to promote a better understanding of the place and mode of use of my invention.

My invention consists of a body 1 preferably curved or arcuate or gutter form in cross section and being slightly less in length than the distance between the opposed edges of the upper central portions of the flanges D, and the distance between the opposed edges of the recesses, sockets or bearings D'. Supporting arms 4 extend in opposite directions from the lower portions of the respective ends of body 1. Preferably said supporting arms 4 are upwardly offset from said lower portions of the respective ends of body 1, being connected thereto by inclined portions 3 and preferably extend horizontally from the respective ends of said body 1, said supporting arms 4 preferably being nearly equal in length to the length of the bearings D' respectively and preferably being curved in cross section in accordance with the degree of curvature of the lower portions of the sockets D' with which they are to be used.

The body 1 is provided with side flanges 2 extending oppositely outwardly from its respective upper edges so as to engage and bear against the opposed inner face of the top portions of the respective members of the hood preferably at approximately equidistant points on opposite sides of the axis of the hinge rod F and preferably at an appreciable distance therefrom to permit an unimpeded flow or drainage through the body or valley 1 of such water as may find ingress through the openings in the joints of the hinge.

The device of my invention will of course be made in different lengths to suit the different makes of cars according to the distances between the cowl A and the radiator B thereof.

Preferably the body 1, flanges 2, inclined portions 3 and supporting arms 4 will all be integral and preferably will all be

stamped from suitable resilient sheet metal stock and formed up by suitable sheet metal stamping operations.

To apply the device of the present invention to an automobile it is simply necessary to raise the hood C of the automobile so as to remove the hinge bar F from its bearings or sockets D' and to then apply the said device with the valley uppermost and the supporting arms 4 disposed in the respective sockets or bearings D' and thereafter to replace the hood C, when the extreme end portions of the hinge bar F will contact the upper faces of the arms 4 and be supported thereby, while the arms 4 in turn will be supported by the upper face of the lower central portions of the respective bearings or sockets D'. As thus positioned and supported the central portion of the valley 1 will be spaced below the opposed lower faces of the interlapped hinge sections or elements of the members of the hood C so that there may be an unimpeded drainage of water through the lower central portion 25 of the body 1, which will be disposed in an inclined position with its front end lower than its rear end whereby the flow of the water will be from the cowl A toward the radiator B, and whereby the water will be discharged from the lower forward end of the body 1 about the inclined portion 3 and against the rear face of the radiator B.

Having thus described my invention, what I claim as new and desire to secure by Letters Patent is:

1. A valley for use upon motor vehicles to catch the drip at the hinge connection of the hood, said valley being of resilient sheet metal with a longitudinally extending body 40 of concave form in cross-section and formed with oppositely outwardly presented longitudinally extending side flanges in operative position pressing against the opposed lower faces of the hood members substantially at equi-distant points from the axis of the hinge, in combination with supporting arms integral with, and upwardly offset from, the lower central portions of the respective ends of the body and respectively 45 extending in opposite directions from their respective ends of said body and adapted to be inserted in, and supported by, the hinge bar bearings and adapted to support, and to be held in position by, the end portions of 50 said hinge bar journaled in said bearings respectively.

2. A valley for use upon motor vehicles to catch the drip at the hinge connection of the hood, said valley having a body of concave form in cross-section, and being 55 formed with supporting arms extending lengthwise in opposite directions from the respective ends of the lower portion of said body and in operative position fitting in, and being supported by, the hood cover

hinge rod bearings and being gripped between the lower face of the respective end portions of said rod and the opposed faces of the respective bearings, said supporting arms being upwardly offset from said lower portions of the respective ends of said valley whereby the upper face of the longitudinally extending lower part of the valley will be spaced from the adjacent opposed lower portion of the composite approximately cylindrical face of the hinge.

3. A valley for use upon motor vehicles to catch the drip at the hinge connection of the hood, said valley having a body of concave form in cross-section, and being formed with supporting arms extending lengthwise in opposite directions from the respective ends of the lower portion of said body and in operative position fitting in, and being supported by, the hood cover hinge rod bearings and being gripped between the lower face of the respective end portions of said rod and the opposed faces of the respective bearings.

In testimony whereof, I have signed my name to this specification at Galveston, Texas, this 10 day of December, 1932.

WILLIAM CLARENCE GARMAN.
